UNITED STATES PATENT OFFICE.

HENRY WENNEBORG, JR., OF SPRINGFIELD, ILLINOIS, ASSIGNOR OF ONE-HALF TO
CHARLES A. ANDERSON, OF SPRINGFIELD, ILLINOIS.

COMBINATION-TOOL.

1,009,609.

Specification of Letters Patent. Patented Nov. 21, 1911.

Application filed March 1, 1910. Serial No. 546,718.

To all whom it may concern:

Be it known that I, HENRY WENNEBORG, Jr., a citizen of the United States, residing at Springfield, in the county of Sangamon and State of Illinois, have invented a new and useful Combination-Tool, of which the following is such a full, clear, and exact description as will enable others skilled in the art to make and use my said invention.

10 This invention relates to devices of that kind which embody in a single tool a plurality of instrumentalities adapted for different uses.

15 The purposes of the invention are to provide a combination tool capable of use in different positions, as a boring or drilling tool; as a bench clamp; and as a vise or saw-clamp, said tool being of light and strong construction and easily portable, and effective for all the uses set forth.

20 With these ends in view the invention consists in the novel features of construction and combinations of parts shown in the annexed drawings and hereinafter particularly described and finally recited in the claims.

25 Figure 1 is a side elevation of the complete tool, some of the parts being shown in section to more clearly illustrate the interior construction; Fig. 2 is a transverse section on the line *v. v.* of Fig. 1; Fig. 3 is a side elevation of the tool as it appears when the saw-clamps are removed, some of the parts being shown in section; Fig. 4 is a vertical section on the line *W. W.* of Fig. 1; Fig. 5 is a partial isometric view of one of 30 the clamping jaws; Fig. 6 is an isometric view of the head of the drill shaft; Fig. 7 is a view of one of the screws which connect the clamping jaws with the tail stock; Fig. 8 is a transverse section on the line *X. X.* of Fig. 3.

35 Similar reference numerals and characters designate like parts in the several views.

40 The tool is preferably constructed of pressed steel, but other suitable material, such as malleable casting, may be used.

45 The frame or main structure 1, comprises a bar of I-shaped cross section, having its ends bent approximately at a right angle to form a head stock 2 and a tail stock 3 integral with the body of the bar, as clearly shown in Figs. 1 and 3. The head stock 2 has a boss 2^a internally screw-threaded to

50 accommodate the thread of the tubular screw 4 turning in said boss. The upper part 4^b of the tube 4 is preferably square.

55 A hand wheel 5 has a square hub 5^a fitting on the square part 4^b of the sleeve 4. At the lower end of the sleeve 4 is an enlargement 4^a, strengthening that part of the sleeve.

60 The tail stock 3 has in its sides longitudinal channels 3^a respectively accommodating the legs 6^a of the dog 6. The dog 6 has a screw-threaded member 6^b adapted to extend 65 through the bar 7.

65 To facilitate the placing of the dog on the frame 1, part of the outer flange of the head stock 2 is cut away, as at 1^a, to permit the legs of the dog to pass the flange and travel in the channels 1^b and 3^a.

70 A nut 8 fits on the screw of the member 6^b and connects the dog with the bar 7.

75 A screw 9 having a square head 9^a screws into and extends through the bar 7 and serves to clamp the bar 7 against a stationary support A, to hold the tool in a vertical position, as shown in Fig. 1, or the dog may be moved and placed on the frame 1 in such position that the same bar 7 and screw 9 may be used to securely connect the tool in a horizontal position on a stationary support A', as shown in Fig. 3, as herein-after more fully described.

80 A shaft 12 fits and turns within the bore 85 of the tube 4, and has at one end a head 12^a provided with a tool socket 12^b, and having a semi-globular or rounded enlargement 12^c, shown in detail in Fig. 6.

85 A square nut 13 is secured at one end of the shaft 12 and bears against the outer end of the hub 5^a of the hand wheel 5. A crank 14 has a square socket 14^a adapted to fit on the nuts 13 and 9^a or the hub 5^a, or the nut 8, or the heads of the bolts 10 and 10'. The bolt 10 is shown in detail in Fig. 7 and the bolt 10' is just like it.

90 A set screw 14^b serves to secure the crank on the hub 5^a, as shown in Fig. 1, or to secure it on the hub 5^a and the nut 13; or to 95 secure it on the nut 13 alone; as indicated by dotted lines in Fig. 3.

100 The screw of the sleeve 4 is preferably a quick acting screw adapted to effect rapid action when boring in wood; and is controlled by the hand wheel to effect slow feed when drilling metal.

105 The tail stock 3 has a screw-threaded hole

3^b in line with the axis of the shaft 12 and accommodating the screw 10' and a longitudinal slot 3^a, the use of which is herein-after explained.

5 The block 15 has a hook-member 15^a, standards 15^b, and a downwardly extending member 15^c. The member 15^a of the block 15 hooks under the flange of the frame 1, and the block is slid able and may be set 10 in different positions on the frame. A screw 16 serves to secure the block in the different positions in which it may be set. The screw has a conical end formed to bear on the edge of the flange to hold the block 15 firmly against the upper side of the frame.

15 The jaw 17, which will be hereinafter referred to as the movable jaw, is connected with the block 15 by a pivot 17^a, so that the jaw will oscillate on the block.

20 The jaw 17 has integral members 17' separated by a space 17^b. It also has a circular depression 17^c in line with the shaft 12 and adapted to accommodate the semi-globular enlargement 12^c of the head 12^a, so that 25 the jaw will have limited universal movement on the end of the head. The jaw 17 also has a central screw-threaded hole 17^d accommodating the screw 10.

25 A plate 18 having a central hole smaller than the circumference of the enlargement 12^c and somewhat larger than the circumference of the head 12^a, is connected with the jaw 17 by screws 19.

30 Springs 20 surround the screws 19 and 35 act to hold the plate 18 against the jaw 17, to form a yielding connection between the jaw and the head, such that the jaw will have limited universal movement without lost motion between the movable parts.

35 The clamp or vise jaws 21 and 21' are exactly alike, so a description of one will suffice for both.

40 The jaw 21 has a hole 21^a accommodating the screw 10 or 10', connecting the vise jaw 45 with the movable jaw 17, or the tail stock 3, as the case may be. It also has an inwardly extending member 21^b fitting in the slot 3^a of the tail stock, or in the space 17^b between the members 17' of the movable jaw, to prevent lateral movement of the vise jaw; and 50 a flat face 21^c, co-acting with a similar face of the complementary jaw to hold a saw or other article between the jaws.

55 The holes 17^d and 3^b are both in line with the shaft 12 in order that when the clamping jaws 21 and 21' are removed a bit or drill seated in the socket 12^b may extend through the hole 17^d to act upon the article held between the movable jaw 17 and the 60 tail stock 3, and also in order that when a hole is bored or drilled through the article, the projecting end of the bit may extend into the hole 3^b, thus avoiding injury to the point of the bit.

65 In case the sides of the article held be-

tween the tail stock 3 and the jaw 17 are not parallel, the ball and socket connection of the jaw 17 with the head 12 will permit the jaw to yield to conform to the surface with which it contacts.

70 To move the jaw 17 quickly toward or away from the tail stock the thumb screw 16 will be loosened, the crank 14 will be secured on the hub 5^a and will be turned to cause the sleeve 4 to slide the jaw 17 and the 75 block 15 to the desired position, and the thumb screw will then be tightened to secure the block in the position in which it has been placed.

75 The several modes of using the tool are as 80 follows: The tool will be secured on a suitable support in a vertical position or a horizontal position, as may be more convenient for the contemplated use. If a saw is to be sharpened it will be placed between the jaws 85 21 and 21' and the handle 5 will be turned to move the jaw 21 to firmly clamp the saw between the jaws.

85 If it be desired to bore wood the screws 10 and 10' and the jaws 21 and 21' will be 90 removed. The article to be bored will be placed against the inner face of the tail stock 3 and the crank 14 will be secured on the nut 13 and the hub 5^a of the wheel 5 and a suitable bit will be placed in the 95 socket 12^b and the crank 14 will then be turned to rotate the tubular screw 4 to cause the bit to bore rapidly through the wood.

90 When the bar 7 is in the position indicated by dotted lines in Fig. 3, the article 100 A to be drilled may be held between the bar 7 and the tail stock 3, and the drill operating thereon will extend through the holes 17^d and 3^b.

105 To drill a hole in metal the procedure will be the same, except that slower feed of the tool to the work will be necessary. To effect this slower feed the crank 14 will be secured on the nut 13 to rotate the shaft 12 and the wheel 5 will be turned by hand from 110 time to time, as may be necessary, to produce the desired feed.

115 If it be desired to drill a series of holes through a plate which cannot be conveniently placed on or against the face of the tail stock, the plate will be placed under or against the back of the tail stock and the tool be held firmly against the plate by any suitable means, and the first hole will be drilled. After the drilling of the first hole 120 a bolt will be placed in the drilled hole and through the slot 3^a of the tail stock and the nut will be tightened to clamp the article against the under side or back of the tail stock in position for boring the next hole; 125 the nut will then be loosened and the article moved a distance equal to the desired distance between the holes and the nut will be tightened to again secure the plate, and this may be repeated until the bolt connecting 130

the plate has traversed the full length of the slot 3^b.

If it be desired to drill more holes through the same plate the bolt will be placed in the hole which was drilled last and the plate will be successively set in the positions necessary for drilling the succeeding holes until the bolt again traverses the length of the slot; and this will be repeated as often as 10 may be desired.

For grinding or polishing, the mandrel of the wheel will be placed in the socket 12^b; the crank 14 will be secured on the nut 13 and will be turned to cause the shaft 12 to 15 rotate the grinding wheel.

In gluing together wood work, or the like, the tool may be used in two different ways, namely: The article to be glued may be placed between the jaws 21 and 21' and 20 the hand wheel 5 be turned to cause the jaw 21 to move and clamp the article between the jaws; or the nuts 8 and 9^a may be loosened to adjust the bar 7 to hold the article between the bar 7 and the tail stock 25 3, and the screw 9^a will be tightened to clamp the bar 7 on the article.

It will be observed that the socket 14^a of the crank 14 fits on the hub 5^a, or the nut 13, or the nut 8, or the head of the screw 9^a, 30 or the head of the screw 10, or the head of the screw 10', and is therefore the only instrument needed for adjusting the tool for all the different uses.

Having fully described my invention what 35 I claim as new and desire to secure by Letters Patent is:

1. The combination of a flanged and channeled main frame having a reduced part to admit the legs of a dog to the channels of the frame; a dog having legs adapted to traverse the channels in said frame; a bar mounted on said dog and a screw mounted on said bar and acting against said frame to clamp the frame in changeable positions on different supports.

2. The combination of a head stock, a tubular screw mounted to turn in the head stock, a shaft rotatable within said screw and having a socket, a tail stock having a 50 screw-threaded hole in line with said shaft, a jaw pivotally connected with said shaft and having a screw-threaded hole in line with said shaft, a clamping jaw mounted on said pivoted jaw, a similar clamping 55 jaw mounted on said tail stock and screws fitting in the holes in said pivoted jaw and said tail stock to connect the clamping jaws with the pivoted jaw and the tail stock respectively.

60 3. The combination of a frame having a head stock and a tail stock, a block slidable on the frame, a jaw pivotally connected with said block, a tubular screw turning in the head stock of the frame, a shaft adapted 65 to rotate within said screw and having a

head provided with a socket and an enlargement, a jaw pivotally mounted on said block and recessed to accommodate the enlargement on the head of said shaft, a plate surrounding the head of said shaft and bearing on the enlargement thereof, screws extending through said plate and connecting it with said pivoted jaw, and a spring surrounding said screws and bearing on said plate.

4. The combination of a main frame having a head stock and a tail stock, a block slidable on the frame, a jaw pivotally connected with said block, a tubular screw turning in the head stock of the frame, a shaft turning in said tubular screw and provided with a head having a socket, and a universal-joint connecting said jaw and the head of said shaft.

5. In combination with a frame, a head stock and a tail stock; a clamping bar mounted on the frame, a clamping screw mounted on said clamping bar and having a polygonal head, a pivoted jaw slidable on said frame, clamping jaws mounted on the tail stock and the pivoted jaw respectively, screws having polygonal heads and connecting said clamping jaws with said pivoted jaw and said tail stock respectively; a tubular screw mounted to turn in the head stock, a hand wheel secured on said tubular screw and having a polygonal hub, a shaft revolvable within said tubular screw and equipped with a fixed polygonal nut, and a crank having a polygonal socket adapted to fit on the nut on said shaft, also adapted to fit on the polygonal hub of said wheel, also adapted to fit simultaneously on the nut on said shaft and the polygonal hub of said wheel, and also adapted to fit on the 95 polygonal head of the screw mounted on said clamping bar and the polygonal heads of the screws connecting said clamping jaws with said pivoted jaw and said tail stock respectively.

6. The combination of a main frame having a head stock supporting a revolvable shaft, and a tail stock having an opening in line with said shaft; a jaw movable on the main frame and having an opening in line with said shaft and in line with the opening in said tail stock; a dog connectible with the tail stock; and a bar connected with the dog and adapted to hold the work in line with the shaft, the opening through the movable jaw supporting one end of the shaft and the opening through the tail stock.

7. A frame having a channeled body, a channeled head stock, and a channeled tail stock; in combination with a dog having members adapted to traverse the channels in the body, the channels in the head stock and the channels in the tail stock; a bar connected with said dog, and means adapted to clamp said bar against articles contacting

with the main frame, and likewise adapted to clamp said bar against articles contacting with the tail stock.

8. A combination tool comprising a main frame, a revoluble feed-screw mounted to rotate on the main frame, a hand wheel secured on the feed-screw and adapted to receive a crank, a tool-holding shaft adapted to turn within the feed-screw and adapted 5 to accommodate a crank, a crank fitting on the hand-wheel and the tool-holding shaft, and a securing device adapted to secure the crank on the hand-wheel and the shaft, or on either of them.
- 10 15 9. A combination tool comprising a main frame, a tubular feed-screw mounted to rotate on the main frame, a hand-wheel secured on the feed-screw and adapted to

receive a crank, a tool-supporting shaft turning in the feed-screw and adapted to 20 receive a crank, a jaw slidable on the main frame and connected with the tool-holding shaft to permit rotation of the shaft, a crank fitting on the hand-wheel and the tool-holding shaft, and a securing device 25 adapted to secure the crank on the hand-wheel and the tool-holding shaft, or on either of them.

In witness whereof I have hereunto signed my name at Springfield, Illinois, 30 this 23rd day of February 1910.

HENRY WENNEBORG, Jr.
